UNITED STATES PATENT OFFICE.

WILLIAM J. REILLY, OF CLEVELAND, OHIO.

SEPARATOR.

SPECIFICATION forming part of Letters Patent No. 752,418, dated February 16, 1904.

Application filed February 14, 1903. Serial No. 143,343. (No model.)

To all whom it may concern:

Be it known that I, WILLIAM J. REILLY, a citizen of the United States, and a resident of Cleveland, in the county of Cuyahoga and State of Ohio, have invented a new and useful 5 Steam-Separator, of which the following is a specification.

When steam passes through an engine in the performance of its work it becomes more or 10 less mixed with the oils or other lubricants in the cylinder and valves and with other foreign substances, which same are carried along with the exhaust in a state of mechanical suspension, together with such water as may be condensed on the way, and in event the steam so contaminated is condensed and the water fed back into the boiler these impurities are very 15 objectionable, because a coating of fatty or greasy substance is soon formed on the boiler shell and tubes, which coating is a poor conductor of heat, and therefore destroys the full efficiency of the boiler, and by keeping the water from direct contact with the shell and tubes permits the fire to burn the metal.

20 My invention relates to an apparatus by which all water, grease, oil, and other foreign matter mechanically suspended can be removed or scrubbed out of exhaust or live steam under a high or low pressure or under 25 a vacuum without the use of any chemical reagents. I attain this object by the construction and arrangement of the apparatus, of which a preferred form is illustrated in the accompanying drawings, in which—

30 Figure 1 is a side elevation of the apparatus, showing one end in section; Fig. 2, a plan view of the apparatus, showing the top plate removed from one end; Fig. 3, a perspective view of the rear end of the apparatus with the mouthpiece removed; Fig. 4, an inside view 35 of the mouthpiece, showing the scattering-plate; Fig. 5, an enlarged horizontal section showing details of the interceptors and their connections; Fig. 6, a rear end view of one 40 corner of the case, showing details of the construction; Fig. 7, a rear view of the upper 45 part of one interceptor, showing its connections; and Fig. 8, a vertical section of same on line 8, Figs. 5, 6, and 7.

Similar numerals refer to similar parts 50 throughout the drawings.

The case of the apparatus is preferably 55 formed rectangular in cross-section and about four times as long and one and one-third times as high as its width and is composed of the side plates 1 and bottom plate 2, on which side plates is attached the top plate 3. The side and bottom plates are preferably cast or wrought in one piece, as shown, and are provided with the stiffening-ribs 4 and 5, the rim-flanges 6 for attaching the top plate, and the end flanges 7 for attaching the mouthpiece 8, and the forward end 9 is contracted, as a funnel, to the outlet-aperture 10 and is provided with the flange 11 for attaching an ordinary 65 pipe leading to a condenser or other receptacle. The top plate is also preferably provided with the stiffening-ribs 12 and 13 and the end flange 14 and is attached on the rim-flanges by the bolts or rivets 15.

70 The mouthpiece 8 is provided with the inlet-aperture 16 and with the annular flange 17 for attaching an ordinary pipe leading from a cylinder or other reservoir. From the inlet-aperture 16 the mouthpiece flares to form 75 the square section 18, at the free edge of which is provided the flange 19 for attaching to the end flanges of the sides and top and bottom by means of the bolts or rivets 20. In the square section of the mouthpiece is 80 formed the diaphragm or scattering-plate 21, in which are provided the radial slots 22 and the smaller apertures 23, which slots and apertures are arranged with their area distributed evenly over the diaphragm and serve 85 to scatter or spread in all directions the steam which emerges from the round inlet-aperture, so that it is evenly distributed throughout the entire square section of the case.

90 The bottom plate of the case is preferably inclined downward from the sides and the ends to the central drain-aperture 24, to which is attached an ordinary drain-pipe with valves, by means of which the water which is removed from the steam and accumulated in the 95 bottom of the apparatus can be conducted to a tank or other receptacle.

On the inside of the case near the bottom of

the sides and ends are provided the flanges 25, on which the division-plate 26 is rested. The division-plate forms a partition between the steam-chamber above and the water and oil reservoir below and prevents the steam from coming in contact with the water and oil after the same have been removed from the steam and accumulated in the reservoir. In the division-plate are a series of rows of apertures 27, which are spaced and arranged to receive the lower ends of the interceptors 28, and at intervals on the division-plate are riveted the transverse angle-bars 29, which stiffen the division-plate and also serve as traps or stops to prevent the separated oil and water from being carried along the division-plate by the steam-current, whereby the same will find its way into the interceptor-conduits 30. At intervals on the inside of the case across the top plate and down the side plates are provided the grooves 31 and 32, which are preferably formed by the flanges 33 and 34, in which grooves are inserted the outer flanges of the angle-bars 35, and at intervals across the case are located the transverse angle-bars 36, the ends of which are attached to the angle-bars 35 on each side by bolts or rivets.

The interceptors 28 are preferably located vertically in the case and are each composed of the forward wall 37, the side walls 38, the rear wall 39, and the rearward-diverging wings 40, the words "forward" and "rear" having reference to the direction the steam travels. I prefer to make the forward and side walls and the wings of the interceptors out of a single sheet of metal bent to the proper shape, as illustrated, and to rivet the rear wall to the sides by means of the flanges 41, as shown. In the form of construction illustrated the interceptors extend from the angle-bars 35 at the top of the case down to the division-plate, and the side and forward walls extend down through the apertures 27 a short distance into the oil-reservoir below. There is thus formed the continuous conduit 30 from the top of the case down through the division-plate into the oil-reservoir.

In the rear walls of the interceptors are cut the tapered tongues 42, with their narrow ends directed downward and cut free of the wall and their upper wide ends preferably including the entire width of the wall. These tongues are bent forward along the lines 43 at their wide upper ends into and diagonally across the interceptor-conduits, so that the narrow lower ends extend forward and are in contact with the forward wall of the interceptors, and in the side walls of the interceptors are provided the apertures or vent-holes 44. The forward walls of the interceptors are preferably riveted to the transverse angle-bars and by an upward extension of these walls to the cross angle-bars at the top of the case. The interceptors are arranged in a se-

ries of rows across the case, and the interceptors of each row are located opposite the intervals in the adjacent rows, whereby the course of the steam is staggered throughout the length of the case. The free edges of the wings of the interceptors in each row are also preferably arranged to overlap or extend beyond the free edges of the wings in the adjacent rows, which serves to increase the staggering of the steam in its course through the case and to compel all particles of the steam to find their way between the wings and into the interceptor-conduits.

When the steam enters the separator through the inlet-aperture, it is first distributed by the scattering-plate, so that it fills the entire section of the case above the division-plate. The greater part of the steam is intercepted between the wings of the interceptors in the first row and strikes violently against the wings and the rear walls of the interceptors, against which walls the steam-current in each interceptor is concentrated. The steam then passes through the tongue-holes and against the bent-in tongues, by which tongues it is deflected downward and to each side and finally passes out through the vent-holes in the side walls of the interceptors. The steam which has passed through between the wings of the adjacent interceptors of the first row is joined by the steam which passes through the vent-holes of these interceptors, and this current is almost entirely caught between the wings of the interceptors in the second row, through which interceptors it passes, as described for the first row, and such steam as may pass between the interceptors of the second row is caught by the interceptors of the third row, and so on through the entire length of the separator.

As the steam dashes against the wings of each interceptor, and is then deflected to dash against the rear wall and thence through the tongue-holes with concentrated force against the inclined tongues, and is finally deflected by the tongues to strike the walls of the interceptor-conduit and then out through the vent-holes, it deposits the greater part of the suspended water, oil, and other impurities on these various surfaces, and the steam thus partially cleansed and purified passes on to the next row of interceptors, by which it is further purified, until after staggering through all the various rows of interceptors it is finally completely separated and cleansed of all impurities and passes out of the outlet-aperture free of foreign substances.

The water and oil which has been deposited on the surfaces of the wings of each interceptor is mostly carried forward by the action of the steam to join that which accumulates on the surface of the rear wall and on the tongues and runs down along the tongues on the continuous surface to the forward wall of the interceptor, along which it more rapidly travels,

and, together with the water and oil which is deposited on the inner walls of the conduit, finally runs down into the reservoir below the division-plate. When a drop of oil or other liquid is allowed to hang in suspension from a free edge or to fall freely into a current of steam, it is well known that the steam will in each case seize and dissipate it into a mist and carry it along with the current; but by my apparatus, having various surfaces, but all joined to form a continuous path into the conduit which leads down into the oil-reservoir, no such seizing and dissipating can possibly occur, and the deposited oil will run slowly at first and then more rapidly along the several surfaces and then down through the conduit to the protected reservoir, beyond the action of the steam-current.

The angle-bars which extend across the top in the case and then down along the sides serve as additional deflectors to prevent the steam from passing around the interceptors at the sides and top, and thus compels it to pass through and among the several rows, and any water or oil which may be deposited on these angle-bars will run down to the division-plate, whence it will find its way into the interceptor-conduits, as heretofore described.

It will be understood that the dimensions and the details of shape, construction, and arrangement can be varied in many ways and that the case instead of being horizontal and the interceptors instead of being vertical can be inclined without affecting the general nature of my invention.

The angle-bar 35 being continuous across the top and being bent down and extending on each side to the division-plate forms with the transverse angle-bars 36 a frame to which the interceptors of each row are attached, whereby all the interceptors of a row can be removed together when the cover of the case is off.

What I claim as my invention, and desire to secure by Letters Patent, is—

1. In a steam-separator, a case, a relatively

small inlet-aperture at one end, a diaphragm adjacent to the inlet-aperture, and radial slots in the diaphragm.

2. In a steam-separator, a series of intercepter-conduits having wings diverging rearward from the sides of the conduits, tongues cut in the rear walls of the conduits with their lower free ends bent forward to join the forward walls, and vent-holes in the side walls of the conduits.

3. In a steam-separator, a series of intercepter-conduits having wings diverging rearward from the sides of the conduits, tapered tongues cut in the rear walls of the conduits with their lower free and narrow ends bent forward to join the forward walls, and vent-holes in the side walls of the conduits.

4. In a steam-separator, a series of intercepter-conduits having wings diverging rearward from the side of the conduits, and openings in the rear wall and vent-holes in the side walls of the conduits.

5. A steam-separator comprising a case, a division-plate in the case forming a chamber above and a reservoir below, intercepter-conduits in the chamber leading through the division-plate into the reservoir, and tongues cut in the rear walls of the conduits having their lower free ends bent forward to join the forward walls.

6. In a steam-separator, a series of intercepter-conduits having tapered tongues cut in the rear walls of the conduits with their lower free and narrow ends bent forward to join the forward walls.

7. In a steam-separator, a series of intercepter-conduits having openings in the rear walls and vent-holes in the side walls of the conduits.

In testimony whereof I have signed my name to this specification in the presence of two subscribing witnesses.

WILLIAM J. REILLY.
